ATTORNEY

UNITED STATES PATENT OFFICE.

LOUIS J. C. LARSEN, OF NEW YORK, N. Y.

ALCOHOL INJECTOR.

Application filed September 28, 1927. Serial No. 222,605.

This invention relates to an alcohol injector, and more specifically to means whereby alcohol or analogous fluid may be forced or directed into a gas pipe to clear the same when 5 the gas in the pipe is frozen.

One of the great annoyances, particularly in cold climates, is the freezing of gas pipes, and my invention includes the provision of an improved construction and arrangement 10 of valve so located in communication with the gas pipe or pipes as not to interfere in any way with the flow of gas, which will not leak and which enables the use of a syringe, or analogous device, to inject alcohol into the 15 pipe to free the same when the pipe is frozen.

It is needless to at length set forth the present methods and difficulties in freeing frozen gas pipes as it is perfectly apparent that the provision of a means for this purpose which 20 will permit the pipe to be freed without uncoupling any portion of the pipe system is of great advantage and produces distinctively new results.

With these and other objects in view, the 25 invention consists in certain novel features of construction and combinations and arrangements of parts, which will be more fully hereinafter described and pointed out in the claim.

30 Figure 1 is a fragmentary plan view illustrating the location and operation of my improved mechanism in connection with a gas pipe line;

Figure 2 is a view in longitudinal section 35 through my improved valve and its support showing a syringe in position for operation;

Figure 3 is a view in elevation of the structure shown in Figure 2, with the dust cap in position and the syringe removed;

40 Figure 4 is an end view of the valve casing;

Figure 5 is a view in section on the line 5—5 of Figure 2.

1 represents a gas pipe main, which may be located in the street, and which is connected 45 by a lead pipe 2 into the house or other building. 3 is a T-coupling connected to the pipe 2, and 4 is a pipe extending to the meter or into the building or other structure.

On one end of the T-coupling 3 a pipe section 5 is screwed and is internally threaded 50 to receive an externally threaded coupling tube 6 on which an internally screw-threaded cap 7 is positioned.

8 represents the casing of my improved 55 valve, which is located in the coupling pipe

or sleeve 6 and spaced therefrom. This casing 8 may be of general cylindrical form, as shown, having a reduced externally screw-threaded nipple 9 at one end which projects through a screw-threaded opening 10 in cap 7, as clearly shown in Figure 2.

The inner end of casing 8 is closed by a perforated cover 11, and a valve 12 is located in the casing and normally engages a beveled seat 13 in the casing. This valve 12 has a post 14 thereon, and a coil spring 15 positioned around the post and located between the valve and the cover 11 exerts pressure on the valve to hold the same normally in closed position.

70 The valve 12 has an angular stem 16 projecting into the nipple 9, and a dust cap 17 is normally screwed onto the end of the nipple 9 to prevent the entrance of dirt and dust in the nipple.

75 The parts above described are installed as a part of the system and provide convenient means to enable the injection of alcohol or other analogous fluid into the pipe to free the same from ice.

80 In connection with the apparatus above described I preferably employ a syringe 18 having a nozzle 19 thereon adapted to be positioned in the nipple 9 and having notches or openings 20 at its end so as to allow the escape 85 of alcohol from the syringe when the nozzle is pressed against the end of the stem 16.

85 Around the nozzle 19 I preferably locate a conical gasket 21, of rubber or other suitable material, which projects into the nozzle 19 90 and prevents any possibility of leakage during the operation of the syringe.

95 The syringe 18 may of course be of any desired construction which will contain alcohol and allow the same to be ejected therefrom, and I have shown said syringe as having a plunger 22 with a stem 23 thereon and a handle 24 on the outer end of the stem.

100 When my improved device is installed and ice forms in the pipe it is simply necessary to fill the syringe 18 with alcohol, then remove the dust cap 17 and position the nozzle 19 in the nipple 9. By pressing the nozzle inwardly the valve 12 will be opened and the syringe 105 can be operated to inject alcohol into the pipe and free the same from ice. When the syringe is removed, the valve will automatically close and there will be no escape of gas and the dust cap 17 can be replaced after the operation is ended.

While I have illustrated what I believe to be a preferred embodiment of my invention, it is obvious various changes and alterations might be made in the general form of the parts described without departing from my invention and hence I do not limit myself to the precise details set forth but consider myself at liberty to make such changes and alterations as fairly fall within the spirit and scope of the appended claim.

I claim:

As a new article of manufacture, a closure for a gas main, including a cap having re-

movable screw-threaded engagement with a line pipe, a check valve in the cap, a casing in the cap in which the check valve operates, a screw-threaded nipple on one end of said casing, and said cap having a screw-threaded opening through which the nipple projects, whereby a closure cap may be screwed onto the end of said nipple.

Signed at New York in the county of New York and State of New York this 27th day of September, A. D. 1927.

LOUIS J. C. LARSEN.
